(Cl. D80—11)

To all whom it may concern:

Be it known that I, Martin M. Drogin, a citizen of the United States, residing in Philadelphia,
county of Philadelphia, Commonwealth of Pennsylvania, have invented a new, original, and ornamental Design for a Display Cabinet, of which the following is a specification, reference being
had to the accompanying drawing, which forms
a part thereof.

cabinet, showing my design;

Figure 2 is a top plan view thereof.

I claim:

The ornamental design for a display cabinet,
as shown.

MARTIN M. DROGIN.
